UNITED STATES PATENT OFFICE

107,292

DESIGN FOR A BEDSPREAD

Clarence M. Jones, Calhoun, Ga.

Application October 21, 1937, Serial No. 72,346

Term of patent 3½ years

To all whom it may concern:

Be it known that I, Clarence M. Jones, a citizen of the United States of America, residing in Calhoun, county of Gordon, and State of Georgia, have invented a new, original, and ornamental Design for a Bedspread, of which the following is a specification, reference being had to the accompanying drawing, forming part thereof, wherein,

The figure is a plan view of a complete bedspread showing my new design.

I claim:

The ornamental design for a bedspread, substantially as shown.

CLARENCE M. JONES.
